UNITED STATES PATENT OFFICE

145,952

DESIGN FOR A MERCHANTISING DISPLAY CABINET OR SIMILAR ARTICLE

Gordon A. Petremont, Boston, Andrew K. Benjamin, Newton Highlands, and Edmund C. Brown, Belmont, Mass., assignors to The Gobelin Company Inc., Cambridge, Mass.

Application October 22, 1945, Serial No. 123,096

Term of patent 14 years

(Cl. D80—11)

To all whom it may concern:

Be it known that we, Gordon A. Petremont, Andrew K. Benjamin and Edmund C. Brown, citizens of the United States of America, residing at 285 Marlborough Street, Boston, Massachusetts, 7 Ipswich Road, Newton Highlands, Massachusetts, and 5 Choate Road, Belmont, Massachusetts, respectively, have invented a new, original, and ornamental Design for a Merchantising Display Cabinet or Similar Article, of which the following is a specification, reference being had to the accompanying drawing, forming a part thereof.

Fig. 1 is a perspective view of a merchandising display cabinet showing our new design; and Fig. 2 is an end elevational view thereof.

We claim:

The ornamental design for a merchandising display cabinet or similar article, substantially as shown.

GORDON A. PETREMONT.
ANDREW K. BENJAMIN.
EDMUND C. BROWN.
